PRIVATE AUTOMATIC BRANCH EXCHANGE SYSTEM

Fernand P. Gohorel, Lyon, France, assignor to
International Standard Electric Corporation,
New York, N. Y., a corporation of Delaware

Application June 22, 1943, Serial No. 491,805
In France August 8, 1939

15 Claims. (Cl. 179—27)

1

This invention relates to new and useful improvements in private automatic branch exchange switchboards by means of which local subscribers can be connected with one another and also with an outside telephone network.

It is customary to arrange special facilities for some or all the subscribers of a P. A. B. X, such as direct connections with the outside network, the transfer of an outside call from one station to another with or without the intervention of an operator, etc.

In known systems such special services were usually provided under selective control by a P. B. X station who had to dial a certain number or depress numerical keys.

The object of the present invention is to provide a P. A. B. X in which simply by pushing a button a P. B. X station may control the performance of special operations, e. g. to obtain direct connection to the outside network, to transfer calls from one station to another, etc.

According to one feature of the invention, a rotary switch is provided with wipers connected to an outside line and has access to the stations of the P. A. B. X which are connected to the terminal bank of the switch.

According to another feature of the invention, the device for controlling the switching of a call from one station to another is associated with the outside line and may be connected with the switches of the local P. B. X connecting circuits.

According to another feature of the invention, a P. A. B. X operator's position is connected with the outside line at a point between the exchange connected with the outside line and the P. B. X station.

Another feature of the invention has to do with the transfer of the call from one P. B. X station to another entirely under the control of the called station and without the intervention of the calling station.

Still another feature of the invention consists in the provision of means at the P. B. X operator's position to cut in on a P. B. X connection and to inform one of the parties engaged in such connection that an outside call is awaiting him. The P. B. X subscribers engaged in a local conversation are advised when such forced listening-in takes place.

According to another feature of the invention, a relay automatic switchboard is provided with local junction circuits and one or more call circuits. A local connection is first established over a junction circuit and a call circuit associated with a connector. Then the call circuit and the

2

connector are released and the talking connection is established over the junction circuit. The calling and called subscribers' stations are supplied with current through a device independent of the connector.

Another feature of the invention consists in the provision of arrangements whereby when the outside line is not free, then one of the local junction circuits remains disengaged and cannot be seized by a P. B. X call. This will insure immediate reply to a call coming from the outside network.

Another feature of the invention provides for the transfer of calls from one P. B. X station to another through a junction circuit, a connector equipment and a call circuit.

Various other characteristic features of the invention will appear from the descriptions which follow of the embodiments of the invention illustrated in the drawings in which:

20 Figure 1 is a general diagram of the automatic switchboard with rotary switches;

Figures 2 and 3 are detailed circuit diagrams of the automatic switchboard with rotary switches;

25 Figure 4 is a general diagram of a relay automatic switchboard;

Figures 5 and 6 are detailed circuit diagrams of a relay automatic switchboard; and

Figure 7 shows the way in which Figures 2 to 3 and 5 to 6 should be connected.

First of all an explanation shall be given of the general operation of an automatic switchboard with rotary switches, reference being made to Figure 1.

35 When a local subscriber such as P₁ wishes to call another local subscriber, such as P₂, he lifts his hand-set. He is connected through a local connection circuit comprising a finder CH and a connector CO. He receives the dialing signal and then dials the number of the subscriber P₂, which results in CO being operated to select P₂'s line. If P₂ is disengaged he lifts his hand-set and, thereby, stops the transmission of the ringing current. The call P₁—P₂ is then established through the circuit CH—CO. If P₂ is engaged the busy signal is sent to P₁.

When a local subscriber such as P₁ wishes to establish a call with the outside network L₁—L₂ and lifts his handset, he will be connected to a local connecting circuit CH—CO as before. When he receives the transmission signal he presses down a button associated with his station which has the effect of transferring the call to a switch CR associated with the outside line L₁—L₂. This switch is put into operation to hunt for P₁'s line.

When the line is found, CR stops and P_1 is connected with L_1-L_2 .

When a call coming from the outside network is received on the line L_1-L_2 , an operator at station PS listens-in on the line. She then operates the transfer key forming part of her station, and comes into communication with the local connecting circuit through the equipment ER. She calls the required station, informs him of the call, and the transfer operation then takes place, as will be indicated in what follows, the station PS being then disconnected from the equipment ER.

When a station such as P_1 is in communication with the external network, and it is desired to effect an operation whereby one operator switches through to another operator, and the subscriber then asks that another local station such as P_2 be connected and the outside line held, the operator presses a button at her station causing the network L_1-L_2 to be held and P_1 to be connected to the local connection circuit CH-CO. The subscriber P_1 dials P_2 's number, and the call is established. In order to obtain the outside call again P_1 presses the button forming part of his station, and in ER the local call is cut off and P_1 placed in communication with L_1-L_2 .

In order to transfer a call from the external network, the station P_1 , for example, first of all switches one operator to another operator who will then be in communication with the subscriber, for example, P_2 , to inform him that he should take the outside call. The subscriber P_2 presses the button forming part of his station which puts the switch CR in operation and which searches for the line of the P_2 station. The subscriber P_1 may now replace his receiver. The local connection circuit CH-CO is released and P_2 is in communication with L_1-L_2 through CR and ER.

A detailed explanation shall now be given with reference to Figs. 2 and 3 of the operation of this automatic switchboard having rotary switches. In the description which follows, the relay contacts which are closed when the relay is energized, are given by placing in front of the numeral designating the spring the letter T, and the contacts which are closed when the relay is de-energized by placing the letter R in front of the number.

Local calls.—When a subscriber, such as P_1 , lifts his handset his line relay A is energized over the following circuit: battery, winding of A, RC_1 , wire of line l_1 , station P_1 , line l_2 , RC_2 and earth. The relay A closes the following circuit for the relay II : earth, TA_2 , winding of relay II , bank contact of the rest position associated with the wiper L, wiper L on the rest position, $R21$, resistance R_1 and battery.

The relay II completes a circuit for relay 7: earth, lower winding of 7, $R83$, contact of the electromagnet RCO of the connector CO, contact of the electromagnet RCH of the finder CH, $T112$, resistance R_1 and battery.

The energizing circuit of the electromagnet RCH is established via: battery, electromagnet RCH , $T111$, $T71$, $R101$ and earth. The electromagnet RCH attracts its armature and opens the circuit of the relay 7 which at $T71$ opens the circuit of the electromagnet RCH causing the wipers of the finder CH to advance by one step. When the armature of electromagnet RCH is released, the circuit of the relay 7 is again completed and this relay recloses the circuit of RCH . Thus the stepping of the wipers of CH is continued until they reach the bank contacts of the calling line whereupon the following circuit is closed for re-

lay 10: battery, windings of relay 10 in series, $T114$, wiper T of CH, bank contact t , TA_1 , winding of relay C and earth. The relays 10 and C become energized.

5 The relay 10 short-circuits its upper winding by $T102$ but is held on its lower winding. At $R101$ it opens the circuit of the electromagnet RCH and the wipers of CH are arrested.

The circuit of relay 1 is completed via: battery, upper winding of relay 1, upper winding of relay 3, $T105$, wiper A of CH, conductor l_1 , station P_1 , conductor l_2 , bank contact b , wiper B of CH, $T104$, lower winding of relay 3, lower winding of relay 1 and earth.

15 The relay 3 whose windings are in opposition does not attract its armature. The relay 1 closes the circuit of relay 2 through the non-inductive upper winding of the relay 5. The relay 2 opens at $R21$ the circuit of the relay II , which drops. 20 A holding circuit for relays 10 and C is completed over $T25$ when the relay II becomes de-energized.

The dialing tone is sent to the calling subscriber over the following circuit: signal generator, $R85$, $R62$, $R43$, condenser Cn_1 , $T105$, wiper A and station P_1 .

The calling subscriber P_1 proceeds to dial the called subscriber's number. Every time the dial opens the circuit, the relay 1 drops and completes 30 the following circuit for the electromagnet RCO of the connector CO: battery, electromagnet RCO , $R81$, $R66$, $R12$, $T22$ and earth. The wipers of CO will thus advance step-by-step under the action of the relay 1 which is itself controlled by

35 the impulses sent out by the dial of the station P_1 . As soon as the first impulse of an impulse series is received the circuit of the relay 5 will be completed by: battery, upper and lower windings of 5, $T26$, $R11$, $R151$ and earth. The relay 5, 40 whose lower winding is short-circuited when 1 is energized, is slow to de-energize and remains up throughout the impulse series in the same way as the relay 2.

When a series of impulses has been received, 45 the relay 5 drops. The relay 2 continues to be held over $T11$.

The switch CO will advance by a number of steps which is equal to the number of the impulses received, and finally stops on the bank contacts of the called subscriber's line.

If the called subscriber is free, the relay 8 will be energized via the following: battery, windings of relay 8, $R53$, $R64$, $T23$, $R143$, wiper T_1 of CO, bank contact t , cable v , winding of relay C of the 55 called station, and earth.

Ringing current is sent to the called subscriber via: the signaling device, resistance $R2$, $R42$, $T86$, $R144$, wiper B_1 of CO, bank contact b , cable v , conductor l_2 of the line of the called station, condenser and bell of the called station, conductor l_1 , wire a in the cable v , bank contact a of CO, wiper A_1 of CO, $R145$, $T87$, $R44$, relay 4 and battery. The relay 4 which is insensitive to alternating current is not energized during the transmission of the ringing current, but is energized when the called subscriber answers. When the relay 4 is energized, it is maintained via: $T41$, resistance $R3$, $T24$ and earth.

The relay 7 is then energized in the following circuit: battery, upper winding of 7, upper winding of 9, $T44$, $T87$, $R145$, wiper A_1 of CO, bank contact a of the called station, lines and called station, bank contact b , wiper B_1 of CO, $R144$, $T86$, $T42$, upper winding of 9, lower winding of 7 and earth. The relay 9, whose two windings in

opposition are energized, does not attract its armature.

The two subscribers are now connected by the following circuit: calling station, wiper A of CH, T105, condenser Cn1, T43, T86, R144, wiper B1 of CO, called station, wiper A1, R145, T87, condenser Cn2, T104, wiper B of CH and calling station.

When the called subscriber replaces his handset, he opens the circuit of the relay 1. The relay 1 becomes de-energized when the calling subscriber replaces his handset.

The relay 2, short-circuited by R141, R151 and earth, de-energizes and at T25 opens the holding circuit of relays 10 and C, which release. At T23 the relay 2 opens the circuit of the relay 8 and at T24 the circuit of the relays 4 and 6. When the called subscriber replaces his receiver, the relay 7 drops after 4 has dropped, its circuit being opened at T42 and T44. The relay 7 is re-energized over its lower winding via R83, contact of the electromagnet RCO, contacts of the electromagnet RCH, multiple bank contacts of CO, wiper L, R24, resistance R1 and battery. The circuit of the electromagnet RCO is then completed via: battery, winding of RCO, R111, T71, R101 and earth. The electromagnet RCO attracts its armature and by its contact opens the circuit of the relay 7 which drops again, opening the circuit of RCO, which releases its armature thus again producing the advance by one step of the wipers of CO. When the electromagnet RCO has released its armature, the circuit of the relay 7 is again completed and the wipers of CO will advance by a further step. It will be seen that by the play of the relay 7, and of the contact RCO, the wipers of CO will advance step-by-step up to the rest position. When the wipers reach this position, the circuit of the relay 7 is opened in the wiper L.

If the called subscriber is engaged when the wipers of CO stop on the bank contacts of the line, the following circuit of the relay 6 will be completed: earth, upper winding of 6, T52, T23, R143 and earth on the wiper T1 through the lower winding of the relay 10, or of the relay 8, depending whether the called subscriber was calling or called in the conversation involved.

A busy tone is, therefore, always sent to the calling subscriber via: signaling device, T62, R43, condenser Cn1, T105, wiper A of CH, bank contact a, line and station P1. When the relay 5 has dropped the relay 6 is held over its lower winding via T63, R51 and T24. When the calling subscriber replaces his handset the release takes place as previously described.

If it is desired to increase the capacity of the private automatic switchboard, two series of wipers are provided on the connector CO, and a relay 14 is added. The first series of wipers A1, B1, T1, and TR1 are connected to the rest contacts of the relay 14, and the second series A2, B2, T2, TR2, to the operating contacts. If the called subscriber is accessible over the first series of wipers the relay 14 remains de-energized. If, however, the called subscriber must be reached over the second series of wipers, which is indicated by the transmission of a certain first digit, the relay 14 will be energized in the following circuit: earth, T24, upper winding of relay 14, bank contact of the position corresponding to the first digit of the subscribers in the second series, wipers T1 of CO, R143, T23, R64, R53, windings of the relay 8 and battery. The relay 8 is not

energized on account of the high resistance of the winding of the relay 14.

The relay 14 is energized and closes its holding circuit at T141 through its non-inductive lower winding.

The sequence of operations previously described is repeated but the wipers A2, B2, T2, TR2, take the place of the wipers A1, B1, T1, TR1.

Communication with the outside network.—

When a call emanating from the outside network is received on the conductors of the line L1—L2 (Fig. 3), ringing current is received by the relay 46 via the circuit: conductor L1, R427, R452, winding of the relay 46, condenser Cn3 and conductor L2.

15 The relay 46 closes the following circuit of the relay 46: battery, RTH, winding of 46, T462, R391 and earth. The relay 46 locks up via: T464, R452 and earth. It closes the circuit of relay 24 in series with the ringing lamp through T465.

20 The relay 21 is energized, and through T211 short-circuits its lower winding which causes the calling lamp to light up through its low resistance upper windings. Through T212 it completes the ringing circuit S0.

25 When the operator depresses the listening key assigned to the outside line which is calling, the following circuit for the relay 36 is set up: battery, windings of 36 in series, spring of the network listening key, and its operating contact, resistance R5 and earth. The relay 36 short-circuits at T361 its high resistance lower winding and holds on its low resistance upper winding. This arrangement is provided to prevent two lines 30 of the outside network, being connected simultaneously when the two network listening keys are depressed. On account of the resistance of the relay 36 and the presence of the resistance R5 in the circuit, no two relays 36 can be energized.

40 The following circuit of the relay 31 is closed: battery, upper windings of 31 and 33, R343, T364, service station PS, T365, R342, lower winding of 33 and 31 and earth. The relay 31 is energized; 45 but the relay 33, whose two windings are in opposition, does not operate. Through 31 the relay 31 closes the circuit of the relay 45, as follows: earth, winding of 45, T311, non-inductive upper winding of 39 and battery.

50 The outside line is held by the following circuit: conductor L1, R427, T452, upper winding of relay 41, T312, conductor L2.

The ringing circuit is opened at R452, and the circuit of the relay 46 at R452. The relay 46 falls off, opening the circuit of the calling lamp and of the relay 21, which opens the ringing circuit S0. The circuit of the busy lamp of the line L1—L2 is completed at T451.

The communication with the operator at the operator's position is established via the following circuit: conductor L1, R427, T452, condenser Cn4, R343, T364, service station PS, T365, R342, condenser Cn5, R426, T312, conductor L2 of the line network.

65 When the outside subscriber has informed the P. B. X operator with whom he desires to be connected, the operator depresses the transfer key. An earth is thus applied through T364 and R343 to the upper winding of 33, the lower winding being then short-circuited. The relay 33 will now pull-up and closes the following circuit of the relay 42: battery, upper winding of 42, T331, T452 and earth.

70 When the operator releases the transfer key,

the relay 33 whose two windings are then fed, releases.

The relay 42, which is slow to release, remains up for a sufficient time to permit the relay 32 to become energized in the following circuit: battery, winding of 32, R382, T422, R331, T452' and earth. The holding circuit of the relay 42 is completed through T322 and T452'.

When the relay 42 is energized, the outside line is disconnected from the operator's station PS, and held via: conductor L₁, T425, resistance R1, T312, conductor L₂.

The relay 32 is then held and via T324, R345, wire M₁ and applies earth to one of the ends of the windings of the relay 11, which causes a local finder CH to be put into operation, as has already been described in the case of a call between P. B. X subscribers.

When the wipers of CH reach the bank contacts of the outside line used, e. g. a₂, b₂, t₂, tr₂, the following circuit of the relay 34 is completed: earth, winding of 34, shunted by resistance R8, T325, wire t₂ in the cable V, bank contact t₂ of CH, T114, windings of 10 in series and battery.

The relays 34 and 10 are energized in series and the relay 10 causes the line finder CH to stop.

Through T341, the relay 34 completes a holding circuit for the relay 31 through the resistance R9. At R345 it disconnects earth from the wire M₁. At T342 and T343 it connects the station PS to the wipers A and B of CH via wiper A of CH, bank contact a₂, wire a₂ of the cable V, T343, T364, station PS, T365, T342, wire b₂ of the cable V, bank contact b₂ and wiper B.

The operator at the station PS can then communicate with the called P. B. X subscriber, e. g. P₁, as has been described in the case of a local call.

The operator advises the subscriber P₁ that a call intended for him is waiting on an outside line.

The subscriber P₁ then presses the transfer button TF on his set. An earth is thus applied to the wiper A₁ of CO and causes the relay 9 to operate, since its lower winding is short-circuited. The following circuit for the relay 15' is completed: earth, T92, winding of 15', T103, wiper DA of CH, bank contact da, wire da₁ of the cable V, winding of relay 38 and battery. When P₁ releases his button, the relay 15' is held by T151'. The relay 38 is not energized in the circuit indicated on account of the resistance of the winding 15'.

The relays 13 and 22 are energized in the following circuit: battery, windings in series of 13, R91, T152', wire T, winding of 22 and earth. The relay 13 is held by T131 on its upper low resistance winding in order to prevent two transfers occurring simultaneously on the same line.

The energizing circuit of the relay 40 through its upper winding is set up as follows: battery, upper winding of 40, T451, R411, T344, wire tr₂ of cable V, bank contact tr₂, wiper TR of CH, R32, T132 and earth. The relay 40 completes the following circuit of the relay 39: windings in series of 39, T401, contact of the electromagnet RCR of the switch CR, R371, R351 and earth.

The relay becomes energized and closes the circuit of the electromagnet RCR of the switch CR as follows: battery, winding of RCR, T392, R371, R351 and earth.

The electromagnet RCR attracts its armature and thus opens the circuit of the relay 39, which

drops and at T392 opens the circuit of the electromagnet RCR which releases its armature, thus causing the wipers of CR to advance by one step, whereupon 39 is again operated and closes the circuit of RCR. The same operations are repeated and by the play of the relay 39 and of the contact of the electromagnet RCR the wipers of CR advance step-by-step.

When the wipers of CR reach the bank contacts which correspond to the station line P₁, the relay 37 is energized in the following circuit: battery, windings of 37, T406, wiper TR of CR, wire tr of the cable U and of the cable V, bank contacts tr' and wiper TR₁ of CO, R142, T82, resistance R10, T133 and earth.

The relay 35 is energized in series with the relay C of the station P₁ in the following circuit: battery, winding of 35, T313, wiper T of CR, bank contact t and wire t of the cable U, bank contact t of CH, TA₁, winding of C and earth.

A circuit for the relay 38 and a short-circuit for the relay 15' is closed via: earth, T321, T355, and T404. The relay 38 is energized and completes its holding circuit via: T381, T422, R331, T452' and earth.

The relays 32 and 42 fall off, their circuits being opened at R382 and at T322. Relays 34 and 10 drop, their circuit being opened at T325. The relay 38 drops, its energizing circuit being opened at T103 and its holding circuit at T422.

The relay 37 drops, its circuit being opened at T132. The relay 2 drops, short-circuited by R11, and the earth at R151'.

When the relay 10 has dropped it opens the circuit of the relay 1, which drops and causes the release of the local circuit, as has been previously indicated.

The relay 40 is held on its lower winding by: T402, T362 and R321.

When the relay 32 has been released the operator's transfer lamp lights up, advising the operator that the transfer has been effected. The operator then releases his outside line network listening key which causes the relay 36 to be released. The relay 40 drops, its holding circuit being opened at T362 and the transfer lamp is extinguished.

The subscriber P₁ is from then on in communication with the external network via: conductor L₁, R421, T452, R343, R364, T354, wiper A of CR and bank contact a, wire a in the cable U, conductor L₁, station P₁, conductor L₂, wire b in the cable U, bank contact b and wiper B of CR, T353, R365, R342, R426, T312 and conductor L₂.

The subscriber station P₁ is fed with current through the relays 31 and 33.

At the end of the conversation when the subscriber P₁ replaces his handset, the relay 31 drops. The relay 45, short-circuited at R311, drops and again connects the outside line L₁—L₂ to the calling relay 46'. The relays 35 and C drop, their common circuit being opened at T453.

The outside line L₁—L₂ is released when T312 opens.

When a P. B. X subscriber wishes to enter into communication with an outside subscriber, he may either ask the P. B. X operator to call the outside subscriber, or he may make this call by connecting himself directly to an outside line.

First, I shall explain how an outgoing call is established by the P. B. X operator.

The P. B. X subscriber such as P₁, lifts his handset and then proceeds as in the case of an inside call to dial the number of the line 1'-1'2 of the P. B. X operator's station. The wipers of

CO stop on the bank contacts a' , b' , t' , tr' , to which the said line is connected.

The ringing current is transmitted over the conductors l' — l'' and operates relay 24 which closes the circuit of relay 24: battery, winding of 24, T241', rest contact and spring l of the "night service" key and earth. The relay 24 is operated and via T241 completes its holding circuit independently of the relay 24'. It completes via T242 the circuit of the calling lamp in series with the relay 21. The relay 21 operates and at T211 short-circuits its lower high resistance winding. The calling lamp lights up. At T212, the relay 21 completes the ringing circuit SO1.

The operator depresses the line service listening key. The circuit of the relay 26 is completed through the resistance R5. Via T261 and T262, the relay 26 connects the lines l' — l'' to the operator's station PS. At R264 it opens the circuit of 24 which drops. The calling lamp is extinguished, the relay 21 drops and opens the circuit of SO.

Through T263 the relay 26 short-circuits its lower high resistance winding, but is held by its low resistance upper winding. This arrangement prevents any possibility of confusion on an outside line if the two listening keys were depressed simultaneously. In this case, the relay 26 could not be energized.

The subscriber P1 is now connected with the P. B. X operator. He gives the number of the outside party to whom he wishes to be connected, and replaces his handset. The operator releases the listening key and the service line l' , l'' , and the equipment of the P. B. X automatic switchboard is also released.

In order to call the outside subscriber, the operator depresses her outside network listening key. Relays 36, 31 and 45 are energized, as was described in the case of the reply to a call originating from the outside network.

The connecting loop of the outside line is completed via: conductor L1, R427, T452, upper winding of relay 41, T312 and conductor L2.

When the P. B. X operator at PS receives the dialing tone of the outside automatic exchange, she proceeds to dial the called subscriber's number which operates relay 31 in the rhythm of the impulses. Upon the first de-energization of relay 31 the following circuit of relay 39 is closed: battery, windings of 39, R401, T453', R311 and earth, and this relay operates.

Upon each operation of 31 its lower winding is short-circuited at T311 whereby the relay is sufficiently retarded not to release during impulse sending. The same thing applies for relay 45, which is also retarded in its release.

The circuit for the transmission of impulses to the outside network is as follows: conductor L1, R427, T452, T393, resistance R7, shunted by the upper winding of 41, T312 and conductor L2. The interruptions are repeated in this circuit by the opening of T312 of relay 31.

When dialing has been completed, the relay 39 drops, and the relay 45 is held by T311 across the upper non-inductive winding of 39.

When the called subscriber answers, the P. B. X operator is placed in communication with the said subscriber and the transfer of the call to the calling P. B. X subscriber takes place in the manner as in the case of the transfer of an incoming call.

I shall now explain how a P. B. X subscriber can get into communication with an outside sub-

scriber without the services of the P. B. X operator.

Assuming that station P1 lifts his handset, the finder CH and connector CO are operated as has been previously explained. When he receives the dialing tone, P1 depresses the button TF of his set. This short-circuits the lower winding of the relay 3 and this relay operates.

The relay 15 is operated over a circuit via T31 and is held after the release of 3 by T151, T24, and earth.

Relay 3 falls off when the subscriber P1 releases his button TF.

The following circuit for relays 8 and 23 is set up: battery, windings in series of 8, R53, R64, T23, R143, wiper T1 of CO on the rest position, T154, R33, resistance R11, wire M, relay 23, R223, R223', R461, R421, R451' and earth.

At R85 the relay 8 opens the dial tone circuit. The relay 23 closes the following circuit for the relay 40: battery, upper winding of 40, R451, R423, R463, T231 and earth.

The circuit of the relay 39 is established via: battery, windings in series of 39, T401, contact 25 of the electromagnet RCR, R371, R351, and earth. At T392 the relay 39 completes the circuit of the electromagnet RCR.

From then on, as a result of the play of the relay 39 and the electromagnet RCR, the wipers of CR will advance step-by-step, as has previously been explained.

When the wipers of CR reach the bank contacts of the line of the station P1 the following circuit of the relay 37 is completed: battery, windings of relay 37, T406, wiper TR of CR, wire TR in the cable U, wiper TR of CH, R32, R46, R61, T153, R153', resistance R10, T82, R142, wiper TR1 of CO on the rest position, wire T5, R221', R221 and earth.

The relay 37 at R371, opens the circuit of the electromagnet RCR and the relay 39 and the wipers of CR stop.

The relay 35 is energized in the following circuit: battery, winding of 35, T373, wiper T of CR, bank contact t and wire t of cable U, TA1, relay C and earth.

Relay 10, short-circuited by the low resistance of the relay 35 drops, opening at T104 and T105 the circuit of relay 1 which releases the local circuit. Relay 15 drops when its holding circuit is opened at T24. Relays 8 and 23 drop, their circuit being opened at T154 and T23.

The following circuit for relay 31 is closed: battery, upper winding of 31, upper winding of 55 33, R343, R364, T354, wiper A of CR, wire a of cable U, conductor l1, calling station P1, conductor l2, wire b of cable U, wiper B, T353, R365, R342, lower winding of 33 and 31, and earth.

Via T311 relay 31 completes the circuit of 45 60 through the upper non-inductive winding of the relay 39. When the relay 45 is energized the connecting loop of the outside network line is completed via: conductor L1, R427, T452, upper winding of 41, R426, T312, and conductor L2.

When the subscriber P1 receives the dialing tone coming from the outside automatic switchboard he operates his dial which produces interruptions in the circuit of relay 31.

The impulses are repeated on the outside line 70 in the same way as when the dialing was by the operator of the station PS.

The relay 37 drops when its circuit is opened at T153. The relay 35 is held by T352, T453, R323 and earth on the wiper T of CR. The relay 75 40 falls off when its circuit is opened at R451.

When conversation is completed and the subscriber P_1 replaces his hand-set first the relay 31 de-energizes and then relay 45. The line L_1-L_2 is released as soon as T312 is opened. The relay 35 drops, its circuit being opened at T453.

The equipment used in the direct connection with the outside network is released.

The P. B. X subscriber may during conversation with the outside network hold the outside line and call another P. B. X station. It is then possible either to continue the conversation between the outside line and the first P. B. X station or to transfer the call to another P. B. X station.

A subscriber such as P_1 , being in communication with the outside network through the line L_1-L_2 relays 15, 31 and 45 are energized.

Without abandoning the outside network, P_1 may enter into communication with another P. B. X subscriber by switching the call from one operator to another operator to whom the subscriber then passes his request. In order to do this he will press the button TF on his set. This operation results in the application of an earth to the wiper A of CR. The relay 33 is operated and then follows the sequence of operations described in connection with the transfer key: the relay 42 is energized, the relay 33 drops, the relay 32 is energized, the line L_1-L_2 is held, a local finder is started, the finder CH is stopped on the bank contacts of the outside line L_1-L_2 , and the relay 34 is energized. The relay 35 is held by R403.

The subscriber P_1 is connected to a local finder via: battery, upper winding of the relays 1 and 3, T105, wiper A of CH, bank contact a_2 , wire a_2 of the cable V, T343, R364, T354, wiper A of CR, bank contact a , wire a of cable U, conductor 1, station P_1 , conductor l_2 , wire b of cable U, bank contact b and wiper B of CR, T353, R365, T342, wire b of cable V, bank contact b and wiper B of CH, T104, lower winding of 3 and of 1 and earth.

The subscriber P_1 may now call another P. B. X station.

If P_1 wishes to continue the outside conversation he again presses the button TF on his set. The relay 3 is energized and earth is applied to the wiper A of CH. At T31 the relay 3 closes the circuit of relay 15 which closes its holding circuit via T151 and T24.

When P_1 releases his button TF, the relay 3 drops and closes the following circuit of relay 38: battery, winding of 38, wire da of cable V, wiper DA of CH, T103, T152, R31 and earth. The relay 38 completes its holding circuit over T381, T422, R331, T452 and earth.

The circuit of relay 34 is opened at R382 and that of relay 42 at T322, relay 32 being de-energized when 382 opens. The relays 34 and 10 drop, their circuit being open at T325. The relay 38 drops, its circuit being open at T103, and at T422. The local circuit is released after the drop at 10.

After the drop of 34 and 42 the subscriber P_1 is again connected to the line L_1-L_2 of the outside network.

A P. B. X subscriber may transfer a communication from the outside network to another P. B. X subscriber. After connecting the other P. B. X subscriber by having the call switched by one operator to the other to whom the subscriber can then state his request, P_1 asks the other P. B. X subscriber to take over the call which is being held on the line L_1-L_2 .

The second P. B. X subscriber then presses on the button TF of his set, and the same operations are performed which have been described in de-

tail in the case of the routing by the P. B. X operator of an incoming call. The relays 9, 15', 13, 22 and 40 are energized. The relay 35 and the relay C of the station P_1 drop. The relay 1 drops. The relay 39 is energized, as is the electromagnet RCR which advances the wipers of CR by the play of the relay 19 and of the contact of RCR.

When the wipers of CR arrive on the contacts 10 of the line of the second P. B. X station, the relays 37 and 35 are energized in series with the relay C of the said station. Then follow the energization of 38 and short-circuiting of relay 15', and the drop of relays 32, 34, 42, 10 and 38. The circuit of 40 is opened at T344 and of 37 at T312. Relay 2 is short-circuited by R11 and the earth at R151.

The local circuit is released and the second P. B. X subscriber is connected to the outside network when the relay 35 is energized and the relays 34 and 42 drop.

Restricted night service.—When the operator of the P. B. X service station leaves her station she depresses the "night service" key.

When an outside call is received on the line L_1-L_2 relays 46', 46 and 21 are energized as previously described.

Via T213 the spring 1 of the "night service" key, and its operating contact, an earth is applied to the wire of the repeating bells at the P. B. X.

Any one of the P. B. X stations may then connect with the line L_1-L_2 . In order to do this, the subscriber will lift his hand-set and dial a certain number, 0, for example. He will then press the button TF on his set.

A free line-finder CH and connector CO are connected with the P. B. X line which answers. When 0 is dialed the wipers of CO advance to the tenth position. The following circuit of the relays 8 and 22' will be closed: battery, windings of relay 8, R53, R64, T23, R143, wiper T in position 10, bank contact n of CO, wire N, spring 2 of the night service key and its work contact, relay 22', T461, R421, R451 and earth.

Relay 40 is energized over its upper winding via: battery, upper winding of 40, T463, R222', T222' and earth.

After the energization of relay 40 the line L_1-L_2 will be connected to the P. B. X station 50 which answers as in the case of a transfer.

In this case the circuit of the relay 37 is as follows: battery, windings of relay 37, T406, wiper TR of CR, wire tr of the cable U, bank contact tr and wiper TR of CH, R32, R46, R81, T153, 55 resistance R10, T82, R142, wiper TR1 of CO on position 10, wire TN, T221', R221 and earth.

The release of the local circuit and the establishment of the connection proceed in the same way as previously described.

It will be noted that when the relay 46 is energized upon the receipt of a call from the outside network, the following circuit of the thermic relay TH is completed: battery, contact and winding of the thermic relay TH, T462, R461', work contact and spring 1 of the night service key, and earth.

If, after a certain lapse of time which is dependent on the operating constants of the relay TH no P. B. X station answers, then the thermic relay TH opens in its contact, the circuit of the relay 46 which drops, and at T455 opens the circuit of the relay 21, which in turn opens at T213 the circuit of the repeating bells.

If the call persists when the relay TH has reverted to rest position the relay 46 will again be

attracted and the same operations are repeated.

It should be noted that when a P. B. X subscriber dials the number for directly answering an outside call when the night service key of the P. B. X operator's station has not been depressed, then the following circuit for the relay 16 will be set up: earth, upper winding of 6, T52, T23, R143, wiper T1, bank contact n, wire N, spring 2 and rest contact of the night service key, resistance R12 and battery. The relay 6 is energized and the calling signal is transmitted to the P. B. X subscriber.

Forced listening.—When an operator at the P. B. X service station routes an outside call by switching it to another operator to whom the outside party repeats his request, then if the called P. B. X station is busy, the second operator would normally receive the busy signal. She may then break into the call as a third party to advise the called P. B. X subscriber that an outside call is waiting.

For this purpose she operates the forced listening key and thus via T363 completes the circuit of the lower winding of the relay 4, which operates. The following circuit of the relay 4 is then completed: battery, winding of relay 4, T61, R46, R32, wiper TR of CH, bank contact tr₂, wire tr₂ in the cable V, T344 and earth. The relay 4 completes its holding circuit via T41, resistance R3, T24 and earth.

The circuit of the relay 8 is completed: battery, windings of 8, R53, T64, resistance R13, T45 and earth.

Via T37 and T36 the P. B. X operator of the service station is placed in communication with the P. B. X stations through the finder CH and the connector CO.

Nevertheless, in order to advise the two P. B. X subscribers that the P. B. X operator will cut in on the call an attenuated busy signal is applied to the line by T62 through the high resistance R14 which in this case is not short-circuited at R43.

If the called P. B. X station accepts the outside call he presses the button TF on his set and the operations take place as previously described.

Figure 4 shows a diagram of a relay automatic P. B. X switchboard. It is assumed by way of example, that this automatic switchboard accommodates six local subscribers and one outside line. It is clear that the number of local stations and outside lines can be increased without departing from the spirit of the invention.

When a subscriber such as BP₁ wishes to call another P. B. X subscriber such as BP₂, he removes his handset, whereupon he is connected with the connector BECR through one of the junction lines BJ₁ or BJ₂. He receives the dialing signal and dials BP₂'s number. If BP₂ is disengaged the connection is completed by the equipment BECR through the connecting line BJc. When BP₂ answers, the two subscribers are connected through the junction line BJ₁ or BJ₂. The connector equipment BECR is released, the connection being supplied with current from the equipment BAL.

When a subscriber such as BP₁ wishes to communicate with an outside line and removes his handset, and is connected to the equipment BECR through the line BJ₁ or BJ₂, then upon the receipt of the dialing tone he depresses a button on his set which results in a transfer of the call to the equipment BELR associated with the outside line. The equipment BECR is released and BP₁ is connected to the outside network through BELR.

When a station such as BP₁ is connected with an outside line and it is desired to have one operator put a call through to the other operator to whom the subscriber then makes his request, BP₁ presses the button on his set. In the equipment BELR the outside line is held and the junction line BJ₁ or BJ₂ is connected to BECR. BP₁ dials the number of the P. B. X subscriber whom he desires to call, BP₂ for example. When BP₂ answers, his station will be connected with P₁ over one of the circuits BJ₁ or BJ₂, the equipment BECR and the circuit BJC.

In order to recall the outside line, BP₁ presses the button on his set once more which in BECR cuts off the local call and connects BJ₁ or BJ₂ to BELR.

In order to transfer a call on the outside line, the station BP₁ first causes one operator to pass the call to another operator to whom the subscriber then makes his request, e.g. that the subscriber BP₂ be informed that there is an outside call for him. The subscriber BP₂ presses the button forming part of his set which causes in the equipment BECR the disconnection of the station BP₁ from the circuit BJ₁ or BJ₂, the connection of the station BP₂ to the said circuit, and the connection of this circuit to the network equipment BELR.

A detailed explanation shall now be given with reference to Figures 5 and 6 of the operation of this relay automatic switchboard.

Local call.—When a P. B. X subscriber such as BP₂ removes his hand-set the following circuit is closed for the relay B9': battery, winding of B9', R691', R491', R291', conductor B1₂, subscriber's station BP₂, conductor B1₁, R293', R492', R692', and earth. The relay B9' is operated and at T94' completes the circuit of the right-hand winding of the relay B8, which is operated because its left-hand winding is energized over T93' through a resistance BR1.

The following circuit of the relay B27 is then closed: battery, lower winding of relay B27, R282, R254, wire d, R472, R241, wire i, T91', T81 and earth. The circuit for the right-hand winding of the relay B29' is closed via: T274, T92', T82 and earth. Via T274' the relay B27 completes the circuit of the relay B47 which operates.

The relay B9' drops, its circuit being opened at R291' and R293'. The relay B8 drops when its circuit is opened at T94' and the relay B27 when its circuit is opened at R472. The following circuit for relay B63 is closed: battery, upper windings of B63 and B64, R851, T471', R251, T291', conductor i₂, subscriber's station BP₂, conductor i₁, T293', R252, T474', R853, lower windings of B64 and B63, and earth.

The relay B64, whose two windings are in opposition and are inserted in the same circuit is not energized.

The circuit of relay B83 is completed as follows: earth, winding of B83, T631, upper non-inductive winding of B84 and battery.

A holding circuit for the relay B47 is closed via: T484, T473, R671', T831 and earth. A holding circuit for the relay B29' is closed via: T292', T473', R672, T832 and earth.

The dial tone is sent to the calling subscriber via: R872', condenser Cn₁, T474', R252, T293 and the subscriber station BP₂.

When the subscriber BP₂ dials the number of the called subscriber the circuit of the relay B63 is interrupted. When the relay B63 drops for the first impulse of each impulse series the relay B84 is energized via: battery, windings in series

of B84, R874', T835, R631 and earth. At each operation of B63, the lower winding of B84 is short-circuited, which retards the said relay sufficiently that it will not be released during the reception of an impulse series.

Upon the reception of the first impulse series the relay B88 is energized over its left-hand winding via: battery, left-hand winding of B88, R881', T843, R632, T834 and earth.

When the relay B63 is again operated after the first impulse the relay B88 is held in series with the relay B88' via T881 and T834. The following circuit is then closed for the relay B89: battery, winding of B89, R892', R902', R912', T882, T834 and earth.

After the first impulse has been received the following circuit of the relay B87' is completed: battery, winding of B87', R875', T843, R632, T834 and earth. The relay B87' completes its holding circuit over T871', T831 and earth and at R872' it opens the dial tone circuit.

When the second impulse is received the relay B88 becomes de-energized because current flows through its right-hand winding via: T881', T834, R632, T834 and earth. The relay B88' is held in the same circuit by its right-hand winding.

When the relay B63 is re-energized after the second impulse the relay B88' drops, its circuit being opened at R632 and it closes its contact R883' at the same time as it opens its contact T882'. The following circuit for the relay B89' is completed: battery, winding of B89', T882, R902, R912, R883', T834 and earth.

The relay B89' opens at R892' the circuit of the relay B89 and locks up via T891', at T892', preparing the circuit for relay B90. Upon the reception of the third and fifth impulses, relays B88' and B88 are energized again, as has been explained for the reception of the first impulse. Upon the reception of the fourth and sixth impulses they drop, as upon the reception of the second impulse.

It will be seen that by the play of the relays B88, B88', B89 to B91 and B89' to B91' upon completion of dialing only the following relays will remain attracted:

- B89 if the number dialed is 1
- B89' if the number dialed is 2
- B90 if the number dialed is 3
- B90' if the number dialed is 4
- B91 if the number dialed is 5
- B91' if the number dialed is 6

Each of these relays prepares the circuit for the one which follows and opens the holding circuit of the one which precedes.

It will be assumed BP₂ wishes to enter into communication with BP₆. He dials 6, and on completion of the dialing the relay B91' is operated and holds over T911', R883', T834 and earth.

If the called subscriber BP₆ is free, the following circuit is closed for relay T1' when the relay B84 drops for a minute after the completion of dialing: battery, winding of B71', T196', R681, R842, T831 and earth.

Ringing current is transmitted to the called subscriber's station via: earth, secondary winding of the transformer R864, T712', R513', R313', conductor I'1, condenser, bell at station BP₆, conductor I'2, R311', R511', T711', R863, winding of the relay B86 and battery.

The relay B86 which is insensitive to alternating current remains operating when the sub-

scriber BP₆ lifts his receiver and locks up via: resistance R2, T861, T831 and earth.

The following circuit for the relay B65 is completed: battery, upper windings of B66 and of B65, T863, T711', R511', R311', conductor I'1, station BP₆, conductor I'1, R313', R513', T712', T864, lower windings of B65 and B66 and earth. The relay B66 whose two windings are in opposition does not operate.

The relay B31' is energized over the following circuit: battery, left-hand winding of B31', T913', T472', R871', T651 and earth. The relay B25 is energized in the circuit: battery, winding of 25, R266, T475', R874, R845, R871, T651 and earth.

The relay B25 opens the circuit of the relay B63 at R251 and R252. The relay B83 is then short-circuited at R631 and drops after a short while. The relay B65 drops, its circuit being opened at R311' and R313'. Relays B41, B71', B86 and B87' drop, their circuit being opened at T831. Relay B91' drops, its circuit being opened at T834.

Relay B46 which feeds the stations BP₂, BP₆ via T251, R682 and via T252 and R684 is operated. The relay B25 is held via R266, T255, T461 and earth. The relays B29' and B31' are held by their right-hand windings, one via T293' and the other by T313 on the earth of T253.

The talking circuit between BP₂ and BP₆ is as follows: BP₂, conductor I₁, T293', T313, conductor I'1, BP₆, conductor I'1, T311', T291', conductor I₂ and BP₂. The two stations are fed in parallel through the windings of the relay B46, as has been described. Upon the completion of communication when the subscribers BP₂ and BP₆ have replaced their hand-sets the relay B46 drops, opening at T461 the circuit of the relay B25, which drops. Relay B25 at T253 opens the circuit of the relays B29', and B31' which drop. The release is completed.

If the subscriber BP₆ is busy the following circuit for the relay B68' would be completed: battery, relay B68', T841, T915', T314' and earth.

The busy signal will be transmitted to BP₂ via the circuit: T684', R862, condenser C_{n1}, T474', R252 and T293'.

In this P. B. X automatic switchboard provision is made for the interconnection of six stations and for one outside line L₁—L₂. Two junction circuits BJ1 and BJ2 are provided within the P. B. X. Usually only one junction line will be needed for local calls, the other remaining available for outside calls.

If one of the junction lines is engaged by a local call between two P. B. X stations, and a third P. B. X station wishes to call another P. B. X station, the same operations as previously described take place when the calling station lifts his hand-set, until the busy tone signal is transmitted.

When the calling subscriber dials the number of the called subscriber, as soon as the first impulse has been received by the relay B63 and this relay operates, it closes the circuit of the relay B87'.

The relay B46 closes the following circuit for the relay B68': battery, winding of B68', T873', R873, T462 and earth.

The relay B68' opens at R681' the circuit of the relay, such as B69 of the called subscriber. It completes the circuit for the transmission of the busy signal to the calling station via T684' and R862 and at T683' it prepares its holding circuit which will be closed upon the completion of the reception of dialing impulses via R844, T831 and earth.

The calling subscriber having received the busy signal replaces his receiver which releases the elements of the equipment BECR, as has been previously described. When the relay B83 has dropped, the relays B87' and B68' drop, their holding circuit being opened at T831.

It will be noted that the circuit for the relay B84 which is energized upon receipt of the impulses is opened by R874'. The relay B87' is operated after reception of the impulse series and relay B84, which drops at the beginning of the first impulse series, can no longer be operated.

Thus accidental impulses which may be transmitted by the dialing impulse are not recorded.

Communication with the outside network.—When a call originating from the outside network is received on the line L₁—L₂ the ringing current causes the operation of the ringing device B80 associated with one of the P. B. X stations which functions as the service station, e. g. station BP1. The subscriber BP1 removes his hand-set whereupon relays B29, B47, B63 and B83 are energized. When BP1 receives the dial tone, he depresses the button TF of his station, applying earth to the upper winding of the relay B64 over T251, T471' and R851. The relay B64, whose lower winding is thus short-circuited is operated. The circuit of relay B67' is completed via T641, T833 and earth. The relay B67' completes at T672' its holding circuit independently of the relay B64'.

At R671' the relay B67' opens the circuit of relay B47, which, however, is slow whereby the circuit of the relay B24 is established as follows: battery, winding of B24, T473', R641, T833 and earth. Relay B24 completes, before B47 drops, the following circuit for the relay B21'; battery, upper windings of B21 and B22, T243, T471, resistance R10, T242, lower windings of B22 and B21 and earth.

The differential relay B22 is not energized.

Relay B24 completes the circuit for relay 41, as follows: earth, winding of B41, T211, upper non-inductive windings of B42, and battery.

Via T414 the relay B41 completes the holding circuit for the relay B24 by means of T247 and R444.

When the relay B41 drops contacts R471' and R474' are closed before T471' is opened. The following holding circuit for the relay B21 is closed: battery, upper windings of B21 and B22, T243, R471', R251, T291, station BP1, T293, R252, R474', T252, lower windings of B22 and B21 and earth.

The relay B87 is energized over T673', R641 and T833.

After B41 has dropped the relay B63 whose circuit is opened at T471' and T474' drops. Relay B83 drops and is short-circuited by R631. Relays B67' and B87 drop, the circuit being opened at T833.

The relay B29 is held as follows: battery, left-hand winding of B29, T292, wire e', T245, resistance R11 and earth.

When relay B41 operates the line L₁—L₂ is looped over T411 and T212 and the self-inductance B23.

The talking circuit is then completed as follows: conductor L1, T411, condenser Cn3, T243, R471', R231, T291, station BP1, T293, R252, R474', T242, condenser Cn4, T212 and conductor L2.

If the outside call is not intended for the station BP1, then it may be transferred to another P. B. X station.

Station P₁ depresses the button TF on his set

which applies earth to the line wires and short-circuits the lower winding of the relay B22. This relay will now be operated by its upper winding. At T221 it completes the circuit of the relay B43 via T413 and earth. When the P₁ releases button TF the relay B22 drops and opens the circuit of B43, but this relay is retarded and, consequently, the following circuit of the relay B47 is closed: battery, winding of B47, R484, T246, T431, R221, T413 and earth.

The relay B47 closes at T471' the holding circuit of the relay B41 over the resistance R10. At T471' and T474 it connects the station BP1 to the connecting equipment BECR. The relay B63 is energized in the manner already described, as is also B83. The holding circuit of the relay B47 is as follows: R484, T473, R671', T831 and earth.

The circuit of relay B87 is now closed as follows: T476', T241, T414 and earth.

The subscriber BP1 receives dial tone and proceeds to dial the called number which we shall assume to be that of subscriber BP2. The same operations as previously described are performed, and finally the relay B69' of the station BP2 is attracted.

In the case assumed, when the subscriber BP2 answers a call the relay B49' is not energized, its circuit being open at R871.

The talking circuit between BP1 and BP2 is as follows: station BP1, T291, R251, T471', condenser Cn2, T663, T691', R491', R291', station BP2, R293', R493', T692', T864, condenser Cn1, T474', R252 and T293.

When the local call has been completed, if the BP1 wishes to take the outside call he will depress button TF on his set which will energize relay B64, as has already been explained, whereupon relay B67' is energized through T641, T833 and earth. The relay B47 drops, its holding circuit being opened at R671'. Via R471' and R474' the relay B41 connects the station P₁ with the equipment BELR.

The relay B63 drops as soon as its circuit is opened at T471' and T474'. The relays B83, B67 and B87 drop as has already been explained. The relays B69' and B86 drop, their circuit being opened at T831 in the same way as B65 whose circuit is opened at T691' and T692'.

When the call has been completed and the station BP1 has replaced the hand-set the circuit of the relay B21 will be opened and the said relay drops. The relay B41, short-circuited at R211, drops again. The line L₁—L₂ is released, its holding circuit being opened at T411 and T212. Relay B24 drops, its circuit being opened at T414.

If BP1 wants to transfer the call to BP2, then the latter depresses his button TF which will operate relay B66 whose lower winding is short-circuited. BP1 replaces his hand-set whereupon relays B63 and B83 drop. The circuit of relay B67 is closed via T662, T661 and earth, and at T671 a holding circuit is closed independently of B66.

The circuit of the dialing relays which is opened at T834 is kept closed at T674'.

When subscriber BP2 releases his button TF the relay B66 drops and the following circuit for the short-circuiting of the relay B29 is closed: battery, resistance R9, R661, T672, T872, T473' and T292, de-energizing relay 29.

The following circuit for relay B85 is closed: battery, winding of B85, R663, T673, R831 and earth. The relay B85 closes at T852 its holding circuit via T652 and earth. At T854 it com-

pletes the following circuit for relay B29': battery, left-hand winding of B29', T893', T472', T671, T854 and earth.

The relay B29' opens at R291' and R293' the circuit of relay B65, which drops. Relays B47, B35, B67 and B86 drop, their circuit being opened at T651 and T652'. Relay B87 drops, its circuit being opened at T476'. The circuit of the dialing relays is opened at T674'.

The station BP2 is now connected with the outside network via: station BP2, T291', R251, R471', T243, T411, conductor L₁, outside network, conductor L₂, T212, T242, R474', R252, T293' and station BP2.

The station BP2 may control the switching of the call from one station to the other in the same way as has been described for the station BP1.

If the P. B. X station wishes to call an outside subscriber the same operations are performed as when P1 answers an outside call and thus obtains connection with the line L₁—L₂.

When the calling subscriber receives the dial tone from the outside network he dials the number of the called subscriber. The relay B21, whose circuit is interrupted at each of the dialing intervals, will beat in the rhythm of the dialing impulses.

When the first impulse of each series is received, the relay B42 is energized via T412, R211 and earth. It is held while the impulse series lasts, its winding being short-circuited at each operation of B21. The relay B41 is slow and remains attracted during the impulse series.

At T421 the relay B42 inserts the resistance R13 in parallel with the self-inductance 23 and the dialing impulses are re-transmitted to the outside network by the opening of the loop of the line L₁—L₂ at T212.

It will be noted that in the course of a call made by the station BP1 with a view to effecting the transfer of an outside call this station receives the busy signal, because the called station is engaged in a P. B. X communication.

A busy station may be apprised of an outside call by depressing a listening-in button EF which is provided only at station BP1. The following circuit is closed for relay B68: battery, winding of B38, T682', T675, wire c, T295, button EF and earth. The relay B68 closes its holding circuit at T683, T631 and earth and a circuit for relay B86: battery, winding of B36, T685, T831 and earth. The circuit of relay B46 is opened at R682 and R684. The relay B65 is energized by: T863, T682 and via T864 and T684 through the two stations in parallel which were previously fed by the relay B46.

The station BP1 is connected in parallel with the call while it is in course of being established. In order to prevent listening-in by a third party on two subscribers in conversation, an attenuated busy signal is applied to the line T684' through the high resistance R15, which is short-circuited at R862.

The P. B. X service station BP1 advises the called P. B. X subscriber of the waiting outside call. When the local call is finished, the connection between the service station BP1 and the called P. B. X station, as well as the transfer of the outside connection take place. It will be noted that if a P. B. X station dials a number which is greater than six where only six stations are provided, the relay B68' will be energized via: T912', T882', T834 and earth. The calling subscriber will then receive the busy signal.

What is claimed is:

1. In a telephone system, a private branch exchange, a plurality of subscribers' stations connected with said exchange, means including a numerically operable switch and controlled by a calling station for establishing a connection between it and a called station, an outside line terminating at the exchange, means including said automatic switch and controlled from a calling station for connecting it with said line, and other means also including said automatic switch controlled by a station for connecting the outside line with any one of said stations.

2. In a telephone system, a private branch exchange, a plurality of subscribers' stations connected with said exchange, a first and a second line finder switch, and a connector switch at the exchange, each of said switches having a bank of terminals and cooperating wipers, a connection between the wipers of each first line finder and a connector, multiple connections from the terminal banks of all said switches to said stations, an outside line terminating at said exchange and connected to the wipers of the second line finder, a connection from the terminal bank of the connector to said outside line, and a connection from the terminal bank of the first line finder to the outside line.

3. In a telephone system, a private branch exchange, a plurality of stations connected with said exchange, a special service position in said exchange, an outside line terminating at said position, means including automatic switches for establishing connections between calling and called stations, means at said positions for controlling said switches to establish a connection between the outside line and any one of said stations, and means at said position for controlling said switches to transfer said last-mentioned connection from one station to another.

4. In a telephone system, a private branch exchange, a plurality of stations connected with said exchange, an operator's position in said exchange, an outside line terminating at said position, means including automatic switches for establishing connections between calling and called stations, means at said position for controlling said switches to connect the outside line with any one of said stations, and means at said stations for controlling said switches to connect the outside line with any station.

5. In a telephone system, a private branch exchange, a plurality of stations connected with it, a special service position, an outside line terminating thereat, a first, a second and a third switch, multiple connections from all the three switches to the stations, means responsive to the initiation of a call on one station for connecting it over the first with the second switch, means at each station for operating the second switch to connect with any other station, means at said position for operating the third switch to connect the outside line with any station, a key at each station, and means responsive to the actuation of said key after the connection of the associated station with the second switch to actuate the third switch to connect with the station.

6. In a telephone system, a private branch exchange, a plurality of stations connected with it, a special service position, an outside line terminating thereat, a first and a second finder switch and a connector switch, each having a bank of terminals and cooperating wipers, connections from the wipers of the first finder switch to the wipers of the connector, multiple connections from the banks of all the three switches to

the stations, a connection from the wipers of the second finder switch to said position and therethrough to said outside line, means responsive to the initiation of a call on one of said stations for operating a first finder switch to connect the calling line with the wipers of said connector, means at the position for operating the second finder switch to select the terminals of any station, a key at each station, and means responsive to the actuation of said key after the connection of the station with the connector through the first finder switch to actuate the second finder switch to select the station.

7. In a telephone system, a private branch exchange, a plurality of stations connected with the exchange, a service position at the exchange, an outside line terminating at said position, a first, a second and a third switch, multiple connections from all said switches to the stations, a connection from the service position to the first switch, means controlled by the stations for operating a first and a second switch to establish connections between a station and the outside line, a first key at the service position, means responsive to the actuation thereof to hold the outside line and to connect a station through the first switch with the second switch, a second key at each station, means responsive to the operation of a second key for connecting the associated station through the third switch and the service position with the outside line, and means at the position for releasing connection through the first and second switches.

8. In a telephone system, a private branch exchange, a plurality of stations connected with the exchange, an operator's position at the exchange, an outside line terminating at said position, a first and a second finder switch and a connector switch, each of said switches having a bank of terminals and cooperating wipers, multiple connections from the banks of all said switches to the stations, a connection from the operator's position to the bank of the first finder, means controlled by the stations for operating said switches to establish a connection between a station and the outside line, a key at the operator's position, means responsive to the actuation thereof to hold the outside line and to connect a station through the first finder with the connector switch, a second key at each station, means responsive to the operation of a second key for connecting the associated station through the second finder and the operator's position with the outside line, and means at the operator's position for releasing a connection through the first finder and the connector.

9. In a telephone system, a private branch exchange, a plurality of stations connected therewith, an operator's position at said exchange, an outside line terminating thereat, a connector at the exchange, means controlled at a calling station for operating said connector to establish a connection with a called station, a first switch for connecting a calling station with said connector, a second switch for connecting the operator's position with any one of said stations, a transfer key at the operator's position, means responsive to the actuation of said key for disconnecting the outside line from the operator's position and for holding it, a connection from the first switch to said operator's position, means also responsive to the operation of said key for actuating the first switch to select the connection to said position, a talking circuit established thereupon with a station through the last-men-

tioned connection, a key at each station, means responsive to the actuation of the key at a station connected with the operator's position to actuate the second switch for connecting the last-mentioned station with the operator's position and therethrough with the outside line.

10. In a telephone system, a private branch exchange, a plurality of stations connected therewith, an outside line terminating at said exchange, a connector switch at said exchange, means controlled at a calling station for operating said connector to connect with any one of said stations, a first and a second finder switch, each having a bank of terminals and wipers cooperating therewith, a connection from the wipers of the first finder switch to the connector, multiple connections from the terminals of all said switches to the stations, a connection from the terminal bank of the first finder switch to the outside line, means responsive to the initiation of a call at a station to operate the first finder to connect the calling station with said connector, a key at each station, means responsive to the operation of said key when the first finder engages the terminals of the associated station to operate the second finder to connect said station with the outside line, and means responsive to the operation of said key when the outside line is connected with the associated station through the second finder switch for operating the first finder switch to select the terminals in which the connection to the outside line terminates, and means operative thereupon for establishing a connection from said station over the second finder to the connector.

11. In a telephone system, a private branch exchange, a plurality of stations connected therewith, a connector for establishing a connection with any one of said stations, a first finder for connecting calling stations with said connector, said connector having a set of terminals connected to said stations and a set of cooperating wipers, an outside line terminating at said exchange, one of the sets of terminals in said connector being connected with said outside line, a second finder switch connected with said outside line, terminals for said second finder switch multiplied to said stations, means operable upon the initiation of a call on one of said stations for actuating the first finder to connect the calling station with the connector, and means operable upon the selection of said outside line by the connector for operating the second finder to connect the outside line with the calling station, and means operative thereupon for releasing the first finder and connector switches.

12. In a telephone system, a private branch exchange, a plurality of stations connected therewith, a connector switch, means controlled by a calling station for operating said connector to select any one of said stations, a first finder operable upon the initiation of a call to connect the calling station with the connector, an operator's position, an outside line terminating thereat, a second finder for connecting a calling station with said position, a first listening key at the operator's position, means responsive to the actuation of said key for connecting said position with the calling station over the second finder, a second listening key at the position, means responsive to the actuation of the second key for connecting the position with interconnected calling and called stations through the operated first finder and connector switches, and means operable when the sound key is actuated for send-

ing a distinctive signal to the interconnected stations.

13. In a private branch telephone exchange system, a plurality of substations, a plurality of local junction circuits, a plurality of call circuits, means including a connector numerically operated by the calling station for establishing a connection between the calling and called substations over a junction circuit and a call circuit, means operative upon the establishment of the connection for releasing the call circuit and the connector employed therein, means for establishing a talking connection between the calling and called stations over the junction circuit used in the connection, and means independent of the connector for supplying current to the talking connection.

14. The system according to claim 13, and means controlled by a substation for operating a connector to transfer a call from one station to another through the junction circuit employed in the connection and a call circuit.

15. In a private branch exchange, a plurality

5 of substations, a plurality of junction circuits, means operative upon the initiation of a call for seizing an idle junction circuit, means for establishing a connection between the calling and called stations over the seized junction circuit, means for preventing the seizure of a busy junction circuit by a calling station, a plurality of outside trunks leading to the exchange, means for seizing an idle one of said trunks for the establishment of an outside connection and for preventing the seizure of busy trunks, and means for preventing the seizure of an idle junction circuit when all said trunks are busy.

FERNAND PIERRE GOHOREL.
